UNITED STATES PATENT OFFICE.

CHARLES S. GOODING, OF BROOKLINE, AND SHERMAN W. LADD, OF SOMERVILLE, MASSACHUSETTS.

LASTING-MACHINE.

SPECIFICATION forming part of Letters Patent No. 423,922, dated March 25, 1890.

Application filed November 19, 1888. Serial No. 291,263. (No model.)

To all whom it may concern:

Be it known that we, CHARLES S. GOODING, of Brookline, county of Norfolk, and SHERMAN W. LADD, of Somerville, county of 5 Middlesex, Commonwealth of Massachusetts, have invented certain Improvements in Mechanism for Lasting Boots and Shoes, of which the following, taken in connection with the accompanying drawings, is a specification.

10 This invention relates to lasting-machines. It is an improvement on that class of machines in which the last is held in the hands of the operator while the upper is drawn and laid by a pair of pinchers.

15 This invention relates, mainly, to improvements in matters of construction distributed throughout the machine. Speaking more specifically, this invention pertains to improvements in the pinchers mechanism, in the 20 mechanism for manipulating the pinchers, in the mechanism for plaiting the leather at the heel, toe, and other places, in the tacking mechanism, and other features of construction, all of which will be more specifically 25 described and claimed hereinafter. It may be stated here that we have also made improvements in other parts of said machine, particularly improvements in the tack distributing and driving mechanism, which form 30 the subject-matter of other separate applications for Letters Patent, Serial Nos. 291,261 and 291,262, filed in the United States Patent Office simultaneously with this.

35 In this application the drawings comprise and represent the entire machine to the end that a clear understanding may be had of the parts which form the subject-matter for the claims hereinafter written and the relation said parts sustain to the tacking and 40 other mechanisms referred to above.

Referring to the drawings, Figure 1 is an elevation representing the right side of the machine. Fig. 2 is an elevation of the left side of the machine. Figs. 3 and 4 are elevations of the rear and front of the machine, respectively. Fig. 5 is a side elevation of the lower part of the machine, representing the treadle-lever and a section of the plaiting mechanism. Figs. 6 and 7 are details connected with Fig. 5. Fig. 8 is a front elevation representing a portion of the mechan-

ism for imparting plaiting movements to the pinchers. Figs. 9 and 10 are details connected with Fig. 8, Fig. 10 being a section on line 10 10, Fig. 8. Fig. 11 is a front elevation of 55 that portion of the plaiting mechanism which is in connection with the pinchers. Fig. 12 is a section on line 12 12, Fig. 11. Figs. 13, 14, 15, and 16 are details connected with Fig. 11. Fig. 17 is a side elevation of the mechanism 60 shown in Fig. 11, and also the mechanism for imparting forward and rearward movement to the pinchers-supporting rod and pinchers. Fig. 18 is a plan view of Fig. 17. Fig. 19 is a section on line 19 19 of Fig. 18. Fig. 20 is a side 65 elevation of the pinchers-lifting bar and its operating-cam. Fig. 21 is an end view of Fig. 20, the extreme end being sectioned on line 21 21 of Fig. 20. Fig. 22 is a plan of the pinchers supporting and lifting mechanism. Fig. 23 is a 70 side elevation thereof, and Fig. 24 is a detail connected with the same. Fig. 25 is a front elevation of the pinchers mechanism. Fig. 26 is a section thereof on line 26 26 of Fig. 25. Fig. 27 is a detail connected with Fig. 25. 75 Fig. 28 is a plan view of the guide-bar. Fig. 29 is a side elevation of the guide-bar and its operating mechanism. Fig. 30 is a front elevation of Fig. 29. Fig. 31 is a side elevation of the mechanism for imparting forward and 80 rearward movement to the tack-driving mechanism. Figs. 32, 33, 34, and 35 are details connected with Fig. 31. Fig. 36 is a side elevation of the tack-driving mechanism. Fig. 37 is a front elevation of Fig. 36. Fig. 38 is 85 a side elevation of the tack-distributing mechanism, made partly in section to illustrate details. Fig. 39 is a section on line 39 39 of Fig. 38. Fig. 40 is a sectional plan view of the tack separating and distributing mechanism. Fig. 41 is a section on line 41 41 of Fig. 40, looking in the direction of the arrow 2. Fig. 42 is a vertical section on line 42 42 of Fig. 40, looking in the direction of the arrow b. Figs. 43, 44, 45, 46, 47, and 48 are 90 details connected with the tack-distributing mechanism. Figs. 49, 50, and 51 are details connected with the tack-driving mechanism. Fig. 52 is a side elevation of the mechanism for operating the plaiting devices. Fig. 53 is 95 a section on line 53 53 of Fig. 52. Figs. 54, 55, 56, 57, and 58 are details connected with 100

Fig. 52. Fig. 59 represents the shoe as prepared for the machine. Fig. 60 represents the shoe after being lasted by the machine. Figs. 61, 62, 63, 64, 65, 66, 67, and 68 illustrate the operation of the machine and the process of lasting as performed by the machine, and will be referred to and more specifically described hereinafter.

The working mechanism is mounted upon a column A, which stands upon the floor. This column is bent rearward (see Fig. 5) and supports on its top end a frame-work designated in its several parts by the letter B. Said frame-work is called in this specification a "head." It supports the working parts of the machine, and to that end it has an irregular formation, with curves and projections to which the working parts are pivoted or otherwise connected, as represented and fully described hereinafter.

In the head B is journaled a shaft D, which constitutes the main driving-shaft of the machine. To that end it is provided with a pulley E, a co-operating friction-clutch F, and a treadle mechanism extending down to the floor and adapted to be manipulated by the workman for stopping and starting the machine. On said shaft D are set the cam and cam-wheels that give proper motion to the mechanism, as hereinafter described.

It may here be stated that the shoe is prepared for lasting by first putting the upper onto the last, drawing it over at the toe, and preferably at the sides also, and there securing it with tacks or other fastening devices, as shown in Fig. 59. It is then taken in hand by the workman and held up to the machine in position for commencing the work, as shown in Fig. 1. The edge of the last, with its upper, is pressed against a guide-piece 10, with the edge of the upper turned or bent inward over the last, all this to the end that it may be in position for the bite of the pinchers. The shoe is supported and turned by the hand of the workman, and in order that the shoe may be easily held in position while the pinchers are drawing and stretching the upper over the last a rest or downhold 12 is provided. Said rest is secured by suitable connections to the machine-head or other suitable support and drops down to the position desired relatively to the pinchers, substantially as represented in Figs. 1 and 4. The shoe is pressed upward against the bottom of the rest, and the position of the rest is such that when the shoe is pressed upward against the same, with its edge bearing against the guide-piece 10, as shown in Fig. 1, the upper will be in position for the pinchers to come forward and clasp the inturned edge of the upper, as referred to hereinafter.

In proceeding further to describe the machine we commence with the gripping devices, by means of which the upper is seized, drawn upward and over the bottom of the last, and held down to receive the fastening-tack, and which also perform the proper plaiting

at the heel and toe or other places, as required. It will be understood that a compound motion is required of this gripping mechanism. First, the jaws of the pinchers must open and close to take hold of the edge of the upper, then the pinchers must rise to stretch the leather, and move over and then down upon the last, all the while holding firmly to the leather, in order to bring it down, tightly stretched, into the proper place for attachment to the inner sole, and there must hold it until the presser-foot or wiper, hereinafter described, is moved forward. The tack is then driven and the operation of the pinchers must be repeated. The pinchers are provided with two jaws 14 and 16, one 14 fixed and the other 16 movable in relation to the fixed one. The pinchers are shown in position for work in Figs. 1, 2, and 4, and for details of construction reference may be had to Figs. 25 and 26. The shank 13 carries the outer or fixed jaw 14. The shank 13 is grooved longitudinally, (see Fig. 26,) and in this groove lies the shank 15 of the movable jaw 16. The shank 15 is confined to the shank 13 by means of a collar 17, which collar is fixed to the shank 13, but allows the necessary vertical movement of shank 15.

The main shank 13 of the pinchers is threaded on its upper end, as shown in Figs. 25 and 26. It is supported on the lever 18, which lever is fulcrumed on a pin 19 in the head B. (See Figs. 22, 23, and 24.) The front end of this lever is provided with a swivel-joint consisting of a cupped ring 24, (see Fig. 24,) having an aperture 21 to receive the pinchers-shank, as shown. The bottom face of said ring bears in a corresponding chamber formed in the nut 22, which nut 22 is threaded to turn on the pinchers-shank 13, and above the ring is a semi-spherical nut 23, also threaded to turn on the pinchers-shank and secured by check-nut above. Its bottom face bears in the ring, and the whole co-operating forms a ball-and-socket joint to support and permit a universal swinging movement of the pinchers. The lever 18 is further provided with a hollow extension 20, having an inner chamber to receive the spring 25. (See Fig. 23.) One end of said spring bears against a lever 26, and its opposite end bears against a thumb-screw W, by which the tension of the spring is regulated. The pinchers-shank and pinchers are thus supported on the lever 26 through the spring 25—in other words, by a compound lever in two sections with an intermediate spring—and this gives a yielding spring tension to the pinchers when they have seized the leather and are drawn upward by action of the lever 26. The lever 26 is also fulcrumed on the pin 19. Its forward end bears upward against the spring 25, and its rear end is connected by a rod 27 with the operating-cam 28, to which end a pin 29 is fixed in the rod 27 and enters a groove in the cam. Said cam lifts and depresses the lever 26, and consequently the pinchers supported thereon. In order to understand the vertical

movement of the pinchers effected by this cam, it may be stated that during this vertical movement, by means of mechanism hereinafter described, the pinchers receive also a front-to-rear movement, in order to advance and then draw the leather over the last after they have gripped it. We will suppose the pinchers to have gripped the leather. This occurs when the pinchers are at their lowest point of depression. At that time they are moved, by the mechanism hereinafter described, farthest to the rear. The cam 28 then operates to depress the lever 26 by the same motion, lifting the pinchers vertically and drawing the leather to stretch it upward, and as the cam 28 advances the pinchers come down, having by other mechanism been moved forward over the last. The pinchers do not here come down as low as they were carried when gripping the leather, but drop sufficiently to place the leather in position for tacking to the inner sole. The pinchers then release their hold upon the leather and, descending farther, go forward to again seize the leather and rise as before. (See Figs. 61, 62, 63, 64, 65, and 66.) The upward and downward movements of the pinchers are effected by the groove in cam 28 through the described intermediate lever mechanism. The lever 18 is extended and made to bear upon the lever 26 at some point in the rear of the fulcrum 19, as shown in Fig. 23, to the end that when the lever 26 is lifted by cam 28 it will engage the lever 18 and depress the forward end thereof, and consequently drop the pinchers to position for gripping the leather. This downward movement of the pinchers is thus preferably made positive both in time and limit. The lifting movement of the pinchers is effected by the downward movement of lever 26, imparted through spring 25, which gives a yielding tension upon the leather, and the limit of tension may be modified and variously adjusted by an obvious adjustment of the spring.

We have in the description of the parts given above referred to a front-to-rear movement of the pinchers, which takes place during the vertical movement thereof, which, with said upward movement, forms a resultant, causing the pinchers to draw up the leather, carry it over the last, and lay it down in position for tacking to the inner sole.

We now proceed to describe the mechanism by which this front-to-rear movement is accomplished, specially referring to Figs. 17, 18, 19. The shank of the pinchers extends through a carrier 30, which carrier comprises a tubular sleeve *a* and a similar tubular sleeve *b*, formed in one piece or block and arranged at right angles to each other. The vertical sleeve *a* is made to surround the pinchers-shank, and the carrier as a whole is supported on prongs 31, 31, which surround and embrace the horizontal sleeve *e*. The prongs are carried upon the front end of rod 32, which rod permits the slight rocking

movement in its bearings to allow the swinging of the pinchers, as referred to hereinafter. A pin projecting from said rod supports a cam-roll 33, which engages the cam 34 on the main shaft, as shown in Fig. 17. Said cam operates to move backward the rod against the tension of a spiral spring 35. Said spring is mounted on a suitable stud projecting from the machine-head *B* and operates the lever 36, which engages the rod 32 through an intermediate stud, as shown. Said spring 35 is connected at one end with a wheel 37, which permits being turned on its supporting-stud, and is provided with a clutch-and-ratchet mechanism, (shown in Fig. 19,) whereby the tension of the spring 35 may be regulated. This spring, as before stated, operates to move forward the rod 32, and consequently the pinchers supported thereon, and this, it will be understood, is the force applied to the pinchers for drawing the leather forward over the last.

The shape of the cam 34 is represented in Fig. 17, and as a further aid in understanding the same it is observed that during a part of its revolution the cam holds the pinchers in their rear position, while the mechanism (to be described hereinafter) operates to cause them to grip the edge of the leather. As the cam advances farther, it releases the rod 32, and the pinchers are advanced over the last by the spring 35, forcing forward the rod 32. The cam advances still farther, allowing the pinchers to remain in their advanced position, while the leather is secured in place to the inner sole, and then a further movement of the cam forces the pinchers backward to the position for taking a new hold upon the leather.

In order that the shoe may be in position for the pinchers to properly take hold of the leather, a guide-piece 10 is provided. Said guide-piece and its operative mechanisms are shown in detail in Figs. 28, 29, and 30. A lever 39 is pivoted to the frame or head *B*, as shown reversed in Fig. 29. It has in one end a roll that engages cam 40. Its opposite end is connected with the bar 41, which slides in a groove in the head *B* and supports on its outer end the guide-piece 10. The rearward movement of the bar is effected by a cam 40, and the forward movement thereof when allowed by the cam is effected by the spring 42, the arrangement of which is obvious. The timing of this mechanism relatively to the other parts of the machine is such as to advance the guide-piece, so that the shoe may be pressed against the same, as shown in Fig. 1 and on an enlarged scale in Figs. 67 and 68, while the pinchers advance and take hold of the upper, and then to withdraw the guide-piece while the upper is being strained upward and carried over the last. The shoe is prevented from slipping out of place after the guide-piece is withdrawn by a rest or downhold 12, against which the shoe is pressed by the workman, as before described. Said downhold consists of a foot 12, formed by a strip or plate

which is adjustably connected to and projected forward from a suitable support *a'* to a point where the pinchers are to grip the upper and serve as an indicator to the workman, 5 whereby to determine the point or part of the upper to be laid hold of by the next movement of the pinchers.

We now proceed to describe the mechanism for opening and closing the jaws of the pinchers for releasing and gripping the edge of the upper. It should be borne in mind that the pinchers in their general movement pass backward, gradually descending to the edge of the upper, and here it is necessary that the movable jaw should be raised, so that the gripping-face of the fixed jaw may pass under and bear against the inner face of the upper, the upper meantime passing in between the pinchers-jaws. It will be observed that the jaws are 15 opened back to the rear, as shown in Fig. 1, so that when the movable jaw is raised it opens the space between the two jaws. In practice the upper jaw should be raised about three-quarters of an inch, and this occurs just before the jaws come back against the upper.

In Fig. 62 of the drawings the pinchers are represented as about to take hold of the upper, the last with its upper being pressed against the end of the guide-piece 10. The 30 edge of the upper extends forward to enter the pinchers as they descend open.

The closing devices are mainly represented in Figs. 25, 26, and 27.

By Fig. 27 is represented a shell 44, which 35 is provided with duplicate chambers 45, in each of which is a spiral spring 46. Said spring is coiled about a central core, as shown in Fig. 27, and connects at one end with a lever 47. This shell is provided with a central 40 opening to receive the pinchers-shank 13, as represented. It is fixed upon the pinchers-shank 13, as represented in Fig. 25, with the ends of levers 47 47 bearing downward upon a collar 48, which collar is attached to the 45 shank 15 of the movable pincher-jaw. The movable jaw of the pinchers is lifted by a cam 49 on the main shaft, which operates through an intermediate lever 50. (See Figs. 20 and 21.) The jaw is forced downward by 50 the springs 46 46, which operate through the intermediate levers 47 47. It will be understood that the leather is held by being compressed between the pinchers-jaw. The holding power is limited to the tension of the 55 springs 46 46. The holding power is required only while the pinchers are closed together, and it is desirable to perform the operation of opening the pinchers without lifting against the holding force, and to obviate 60 this in part we arrange the levers 47 47 so that they will be in a nearly horizontal line when the pinchers are closed, as represented in Fig. 25. In this position of the levers the resultant force produced by the springs 46 46 65 operates downward upon the pinchers-jaw in a nearly straight line, and from this point upward as the pinchers are lifted the forces

of the springs 46 46 are decreased by the variation in the angles of the levers to the collar, so that the higher the pinchers are lifted 70 the smaller will become the downward or closing force. This, we believe, to be a new feature in pinchers mechanism. The shape and position of cam 49 is such as to throw the lever 50 and lift the movable pinchers-jaw immediately after the nailer advances, as hereinafter described. The first movement is sufficient to cause the jaw to release the leather, and this we prefer to have take place just before the nailer and presser-foot, hereinafter described, 80 reach their extreme forward movement. The further lifting of this jaw takes place during the backward movement of the pinchers, and immediately after the fixed jaw reaches the edge of the leather the rear end of lever 50 is 85 released by the cam and the movable jaw is forced down to grip the upper. It is forced down by means of springs 46 46, as above described. It remains constantly in contact with the leather until lifted by the movement 90 of the cam and intermediate lever 50. Only the movements of the pinchers mechanism, heretofore described, are necessary on the sides of the last.

In order to form the plaiting at the heel 95 and toe and occasionally at other points, another movement is required. For this purpose it is necessary that the pinchers should have a lateral movement. It is also necessary that such movement should be adapted to yield 100 as required, to prevent tearing the upper, and it is further desirable that such movement should be arranged to take place only when the operator wills it.

In order to permit the necessary swinging 105 movements, the fork ends or prongs 31 31, Figs. 17 and 18, are made to surround the horizontal sleeve *b*, thereby supporting the carrier 30, and also permitting a slight rocking movement of the sleeve in its supporting-bearing, 110 which allows a swinging movement of the pinchers in one direction, and the rod 32 permits a rocking movement in its bearing, which allows a swinging movement of the pinchers in the transverse direction.

In the sleeve *b* is a rod or plunger 51. (See Figs. 15 and 16.) Said rod is movable endwise in the sleeve, and is provided with a pin 52, which extends outward through an opening in the sleeve and engages the springs 53 120 53, as fully shown in Figs. 11 and 12. Said springs are coiled about supporting-studs extended from the carrier 30, and are provided each at one end with adjustable washers 54 54, whereby the tension of the spring may be 125 adjusted. The opposite ends of the springs are respectively made to bear on opposite sides of the pin 52. This mechanism is fully illustrated in the drawings and particularly in Figs. 11 and 12. The tension of the springs 130 53 53 is opposed each to the other. The springs engage opposite sides of the pin 52, and, opposing each other, hold the pin in line with the vertical rod of the pinchers-shank or ap-

proximately in line therewith. This determines the normal condition of the rod 51, and the springs are stopped from crossing the center line by stop-pins 400 and 300, but permits a movement of the rod 51 in either direction, which movement is transmitted to the pinchers-carrier, and consequently to the pinchers, through the intermediate springs 53 53. In other words, a movement of the rod in one direction is transmitted by one of said springs, while a movement in the opposite direction is transmitted by the other of said springs, and this, it will be understood, gives a yielding tension to the lateral movement of the pinchers. This is the power applied to strain the leather in a lateral direction for purposes of plaiting the toe and heel or other places. The lateral movement of rod 51 is imparted through the connecting-rod 55, which is connected, at one end with the rod 51 by a swinging or ball-joint connection, as shown in Fig. 12, in order to permit the necessary movements of the pinchers. The opposite end of said rod 55 is connected with a movable crank-pin 64 (see Fig. 8) through an intermediate yoke 66. The crank-pin 64 is supported in a sliding block 63, which is supported on a rocking driver-head 57, and is arranged to permit sliding movement along the groove 62, formed in the driver 57. Said groove 62 is made to cross the axis of rotation of the driver, and is preferably made curvilinear. Rocking movement is imparted to the driver by mechanism hereinafter described. Obviously while the pin 64 is in line with the center of rotation of the driver the driver will simply turn the pin 64 and impart no movement to the pinchers mechanism. If, however, the pin 64 be carried along the groove 62 to one side of the center of rotation, it will act as a crank-pin and force the rod 55 in one direction, carrying with it the pinchers to one side of their normal position; but if the pin 64 is moved along the groove to the other side of the line of rotation it will operate to draw the rod 55 and carry the pinchers in the opposite direction to one side of their normal position. The object of this twofold motion is to draw and plait the leather at one time in one direction and at another time in the other direction.

The driver 57 is rigidly attached to or formed integral with a sleeve-shaft 56. (See Figs. 8, 10, and 52.) Said sleeve 56 is journaled in a boss or horn extending from the head B, and carries on its opposite end a sectional gear 58, that meshes with a segment-gear 59 on the end of lever 60. Said lever 60 is pivoted to the head B, as shown in Fig. 8. It engages its rear end with a cam 61, which cam is on the main shaft of the machine and operates to rock the lever once in each direction during the revolution of the shaft. This operates to rock the sleeve 56, and consequently the driver 57, which is on the forward end thereof, and which supports the pin 64, as

before described, which pin in turn supports the bar 65. Said bar has its ends journaled in the yoke 66 of the rod 55 and permits rocking movement on the pin 64. The opposite end of said yoke connects adjustably with the rod 55. All these parts are fully represented in Fig. 8 of the drawings.

It is desirable, as before stated, that this plaiting mechanism shall be subject to the control of the workman, so as to be thrown into or out of operation at any time and varied in extent. To this end we provide mechanism as follows: Extending from the column A (see Fig. 5) is a boss, on which is pivoted a lever 68. Said lever is provided on its front end with a fork 69 to receive the knee of the workman. In the rear end of said lever is a cam-groove to receive the cam-roll 70. Said roll turns on a pin projecting from the rod 71. The cam-groove is cut on an incline, as shown in Fig. 6 at 72. A movement of the lever in one direction past the center line lifts and a movement thereof past the center line in the opposite direction depresses the rod 71. The top end of said rod connects with a bell-crank lever 73, (see Fig. 52,) which lever has on its end a fork embracing the collar 74. (See Fig. 53.) Said collar is arranged to slide on the sleeve-shaft 56. It is grooved and splined therewith to prevent turning independently thereon. Attached to the collar is a key 75, which passes through a groove cut longitudinally through the sleeve and enters a groove cut spirally in the shaft 76. (See Figs. 55 and 56.) Said shaft 76 permits rotary movement in the sleeve and carries on its forward end a gear 77, that engages the gear-teeth formed in the slide 63. (See Fig. 9.)

From the foregoing description it will be understood that the driver 57 is given a continuous rocking movement, but imparts no motion to the pinchers mechanism so long as the pin 64 is in line with the center of rotation of the driver. Such is the position of the pin while the lever 68 is extended in a substantially straight line forward, in which position it is supported by a spring-stop, as shown in dotted lines, Fig. 5. This is the normal condition of the lever, and a movement thereof to one side lifts the rod 71, which movement is transmitted through lever 73, collar 74, key 75, shaft 76, and gear 77 to the slide 63 and moves the slide, thereby carrying the pin 64 along the groove 62 to one side of the axis of rotation of the driver 57. The lateral movement of the pinchers then begins, and the extent thereof is determined by the position of the pin 64 relatively to the said axis of rotation, and this in turn is limited by the extent to which the lever 68 is moved laterally from its central or normal position. A reverse movement of the lever 68 will operate to carry the pin 64 off the center of rotation in the opposite direction.

The lever is designed to be moved by the

knee of the workman, and the limit of movement allowed is regulated by the set-screws 79 79, Fig. 7.

In performing the plaiting around the toe 5 of the shoe it is desirable to have the pinchers pass over to one side of their normal perpendicular position, and, starting from that point, to move forward and grip the edge of the leather, lift upward, then backward to the 10 starting-point, and thence pass to the opposite side of the perpendicular line for laying the plait. This movement of the pinchers lays the plait in a line more nearly perpendicular to the curve of the last, and thus prevents the leather from being crimped along 15 the edge of the last. To this end we arrange the pin 64 so as to travel in a curvilinear path on the driver 57, (*i. e.*, the groove 62,) as this construction gives a more uniform 20 advance movement of the pitman 55, and consequently a more uniform movement of the pinchers laterally.

We would not be understood as saying that the pin 64 must be moved in a curvilinear 25 path, as we are aware that a straight path across the center of rotation would be efficient, though it will not result in so uniform a movement of the pinchers as when the pin moves in a.

30 We now proceed to describe the tacking mechanism. It will be understood that after the pinchers have gripped the leather and laid it down upon the last the tacking mechanism is moved forward into position for driving the 35 tack, and again is moved backward to allow the next operation of the pinchers. To this end we provide a carriage N, Fig. 1, having a lateral extension 84 and a vertical extension 85. (See Fig. 36.) The lateral extension 84 is arranged to permit sliding movement in a 40 groove formed in the head B. Connected therewith is a lever 87, (see Fig. 31,) which engages a cam 88 on the main shaft, whereby the carriage is moved forward and backward 45 over the last during each revolution of the cam. The tack-hammer bar comprises the jointed bar 90 90, arranged to permit vertical movement in a groove formed in the vertical extension 85 of the carriage N. (See Fig. 36.) 50 The hammer-bar is lifted by a cam 91, the shape of which is represented in Figs. 32 37. Said cam is mounted on the end of a sleeve 92. (See Figs. 33 and 34.) This sleeve is arranged on the main shaft D, and is grooved 55 and splined thereto so as to revolve therewith for lifting the hammer-bar, and permits sliding movement on the sleeve to accommodate the forward and backward movement of the carriage N. The hammer-bar 90 is lifted 60 against a spring 93, (see Figs. 1 and 2,) which, being contracted by the lifting operation, operates to depress the hammer-bar whenever the cam permits it, and this, it will be understood, is the power which drives home the tack. 65 The tacks are received from the distributing mechanism (hereinafter explained) by a polished steel chute having a raceway, along

which they are conducted to the separating and delivering screw 81, Figs. 38 and 40. Said screw drops the tacks one at a time into the 70 vertical tube 82, through which they descend to a chamber in the tack-holder S, whereby they are supported and carried forward to the driving-point. (See Figs. 49, 50, and 51.) To this end the said holder S is secured to the 75 bottom of the carriage N, (see Figs. 1 and 2,) and is moved forward and backward therewith. Said holder, by the rearward movement of the carriage N, is brought into position with the tack-receiving tube 83 directly under and 80 in line with the tube 82. The tack is dropped through the tube 82 into the chamber 83 of the holder while the pinchers are gripping and drawing the leather over the last. The carriage N is then moved forward, carrying the 85 holder and the hammer-bar into position for driving the tack. During this forward movement the tack remains lodged in the holder S. Said holder S comprises the two blocks f, f, which are pivotally connected. (See Fig. 51.) 90 The blocks are brought together by springs 95 95, and the hammer-bar in descending passes into the tube 83, thereby spreading the blocks f f against the action of the springs 95 95 and releasing the tack at the moment 95 of driving.

Connected with the holder S is a spring 96, located under the holder and having an opening coinciding with the chamber 83. During the forward movement of the carriage N this 100 spring 96 bears upon the leather and wipes over the edge thereof, drawing and retaining it in position for the driving of the tack. The tack in driving passes through the opening in this spring. The hammer-bar is made in 105 two parts 90 90, to the end that the bottom section may be swung forward and permit the holder S to pass under the receiving-tube 82, as shown in Figs. 2 and 36. A rod 94 arrests the rearward movement of this lower section 110 of the hammer-bar, thereby causing it to swing forward, as shown in Fig. 36, and allow the tack-channel block to have place over the tack-holder S. During the forward movement 115 of the carriage N this section of the hammer-bar is forced back to its normal condition by a spring 202. By thus forming the hammer-bar in two parts and swinging the lower section forward and backward, as described, we obviate the work of lifting the hammer-bar 120 high enough to clear the end of the raceway-block, and thereby diminish the time required to lift the hammer-bar.

The tacks are distributed and deposited in the tack-raceway, with their heads bearing 125 upon the sides of the chute, their points projecting downward into the raceway by mechanism described as follows: A shaft 204 is provided with a spiral gear 205, that engages with a similar spiral gear q, Fig. 2, on the 130 main driving-shaft D, from which power is transmitted through said gears to revolve the shaft 204. The motion of said shaft 204 is transmitted to revolve the shaft 206 through

intermediate mechanism composed of the gears *e e*, shaft *h*, worm *d*, worm-gear *n*, shaft *t*, and gears *k k*, (see Fig. 42,) the effect being to revolve the pot 100, which is mounted to turn with the shaft 206. Said pot is closely adjacent to and turns in sliding contact with the basin 207, which basin opens at its rear end into the pot 100. The tacks are placed in bulk in the basin 207, and gravitate down its inclined faces into the pot, and are lifted by paddles 208, secured to the pot, to a point above the pan 209. Said pan is provided with inclined faces (see Fig. 46) converging to a point above the raceway 210 in the channel-block. The tacks in falling from the paddles 208 strike into the pan 209 and pass down its inclined faces head or point first, in either of which cases they shoot off the pan into the raceway, where they are suspended with their heads bearing upon the edges of the chute along the raceway 210. Tacks which are not lined point first or head first by the inclined faces, so as to fall into the raceway 210, fall back into the basin, to be again lifted and dashed into the pans, as before. Obviously some of the tacks will be improperly suspended in the raceway and obstruct the downward progress of other tacks. These improperly-suspended tacks must be lifted from the raceway or adjusted so as to pass downward along the raceway with the other tacks. On the channel-block is a bridge 214, which overhangs the raceway 210. This bridge obstructs the downward progress of all tacks not properly suspended in the raceway—that is to say, in other words, a tack must be down upon the channel-block, its head bearing closely on the surface of the block and its point in the raceway, in order to pass freely under the bridge. Once under the bridge it is no longer liable to displacement. Above the bridge is a tripper 211. Said tripper is supported in the rock-shaft 212. Its bottom end bears upon the channel-block above the raceway, and its end is preferably grooved to receive the edges of the channel-block, as shown in Figs. 40 and 41. The tripper permits movement vertically against the spiral spring 213, which is arranged about the shank of the tripper and operates to bear it down upon the channel-block. The vertical movement of the tripper against said spring permits it to be reciprocated along the raceway-block and also to be lifted onto the bridge 214, as shown in Figs. 41 and 44. To this end a rocking movement is imparted to the shaft 212 by the revolving pot 100 through intermediate mechanism consisting of the lever 215, engaging stops 216 on the pot, an arm 217, and a spring 218, arranged as represented.

Fig. 44 represents the tripper resting on the bridge, where it has been lifted by the return movement of the spring 218. The tripper is shown as engaging and about to move forward along the raceway to agitate and re-

adjust the tacks which are improperly suspended in the raceway. To this end the tripper, after leaving the bridge, is depressed by the spring 213 into contact with the channel-block and moves upward along the channel-block, pushing before it the tacks. The tripper is then withdrawn quickly onto the bridge and the tacks return downward along the raceway. In many cases the tacks will have been adjusted by a single movement of the tripper, so as to pass under the bridge; but a second or third movement of the tripper will accomplish the desired result in all cases. To this end the tripper is moved forward regularly, its action being useless, of course, but harmless, except when tacks are in condition for adjustment. After passing the bridge the tacks gravitate downward to a distributing device, consisting of the worm-shaft 81, whereby they are separated and dropped one by one to the tack-holder *S*. To this end the screw-shaft 81 is made to revolve by gears *r*, Fig. 41, connecting shafts *h* and 81, the shaft *h* being connected to the main driving-shaft 204 by gears *e e*, as shown, and the shaft 81 is caused to drop a tack for each operation of the driving mechanism, as before described. The pot 100 is revolved continuously, and the tacks are thereby lifted and dashed into the pan 209 to pass therefrom into the raceway, as before described.

This tack-distributing mechanism and the driving mechanism, in part, form the subject-matter for other applications for Letters Patent to be filed in the United States Patent Office, Serial Nos. 291,261 and 291,262.

We claim and herein desire by Letters Patent to secure—

1. In a lasting-machine, the combination, with a lever composed of two pivoted members, each member adapted to engage with the other member intermediate the pivotal point and the outer end of said other member, of a pinchers mechanism secured to the outer end of one of the members and an operating device secured to the outer end of the other member, substantially as described.

2. In a lasting-machine, the combination, with a lever composed of two pivoted members, each member adapted to engage with the other member intermediate the pivotal point and the outer end of said other member, of a spring interposed between the contact-point of one of the members with the other member, a pinchers mechanism secured to the outer end of one of said members, and an operating device secured to the outer end of the other member, substantially as described.

3. In a lasting-machine, a pivoted lever, as 26, means for lifting and depressing the same, a lever 18, arranged to have positive engagement with the lever 26 during the uplifting movement thereof, a pinchers mechanism jointed to and supported by the lever 18, and a yielding device interposed between the le-

vers, against which the lever 18 and pinchers mechanism are lifted, substantially as described.

4. In a lasting-machine, and in combination, the pivoted lever 26, means for lifting and depressing the same, the lever 18, pivoted to the inner end of the lever 26 and having one end extended and bearing upon the lever 26, a pinchers mechanism supported by the lever 18, and a spring 25, interposed between the levers, substantially as described.

5. The combination, in the pinchers of a lasting-machine and with the fixed jaw thereof, of a movable jaw and spring-actuated levers mounted on the fixed jaw and engaging with the movable jaw, the whole arranged, as described, so that the power of the levers decreases as the movable jaw moves from and increases as it moves toward the fixed jaw, substantially as described.

6. The combination, in the pinchers of a lasting-machine and with the fixed jaw thereof, of a movable jaw and spring-actuated levers engaging therewith, said levers being substantially at right angles to the line of movement when the pinchers are closed, substantially as described.

7. In a lasting-machine, in combination, the pinchers, shank 13, supporting the lower pinchers-jaw, the shank 15, carrying the upper jaw and movable relatively to the shank 13, and spring-actuated levers carried by the shank 13 and adapted to bear on a collar 48 for closing and compressing the jaws, substantially as described.

8. In a lasting-machine, the combination of a pinchers mechanism and a pivotally-connected supporting-carrier therefor, a rod 51, supported movably in the carrier, and springs 53 53, interposed between the rod and carrier, and means for moving the rod, substantially as described.

9. In a lasting-machine, and in combination, the carrier 30, a pinchers mechanism supported thereby, a rod 32, connected with and supporting the carrier, and means for giving thereto a rocking movement, substantially as described.

10. In a lasting-machine, and in combination, the rod 32, a pinchers mechanism pivotally supported thereon, a cam for advancing the rod in one direction, and a spring for moving the rod in the opposite direction, substantially as described.

11. In a lasting-machine, and in combination, 55 the driver 57, means for giving said driver a rocking movement, a pin supported movably in the driver, and a connecting-rod attached to said pin and communicating with a pivotally-supported pinchers mechanism, substantially 60 as described.

12. In a lasting-machine, and in combination, the driver 57, having groove 62, a slide, as 63, movable in said groove, a rod pivotally connected with the slide at one end and with a 65 pivotally-supported pinchers mechanism at its opposite end, and means for giving the driver a rocking movement, substantially as described.

13. The combination, with the suspended 70 shank carrying pinchers at the lower end, of a rod connected therewith below the upper end, a driver vibrating on a fulcrum between its ends, and a slide connected with said rod and movable on the driver across the fulcrum 75 thereof, substantially as set forth.

14. In a lasting-machine, and in combination, the driver 57, means for giving said driver a rocking movement, a pin supported to slide across the fulcrum of the driver, a treadle device connected with the pin, and a rod connected with said pin at one end and at the other with a pinchers mechanism pivoted at the upper end, substantially as described.

15. In a lasting-machine, and in combination, 85 the driver 57, mounted on the sleeve 56, as shown, means for rocking the sleeve, a groove 62 in the driver, and a slide 63, arranged to travel therein, a shaft located in the sleeve 56 and connected by a suitable gear mechanism 90 with the slide 63, and the described treadle and intermediate connecting mechanisms for giving a rocking movement to the shaft 76, substantially as described.

16. In combination, in a lasting-machine, 95 with a movable rod, as 13, the springs 53 53, means for moving the rod against the tension of said spring, and means for supporting the rod and spring, substantially as described.

Signed at Boston this 15th day of November, 1888.
